(57) **CLAIM**

The ornamental design for a loupe, as shown and described.

DESCRIPTION

FIG. 1 is a perspective view of a loupe showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a first end elevational view thereof; and,

FIG. 7 is a second end elevational view thereof.

The characteristic feature of the design resides in the contrasting and/or layering of material overlying the bottom edge, most easily seen in FIGS. 1, 4, 5, 6, and 7.
